UNITED STATES PATENT OFFICE.

CALVIN DOANE, OF BRAINTREE, MASSACHUSETTS.

DESIGN FOR STOVES.

Specification forming part of Design No. 298, dated July 9, 1850.

To all whom it may concern:

Be it known that I, CALVIN DOANE, of Braintree, in the county of Norfolk and State of Massachusetts, have invented or produced a new and useful Design for the Front and Back Plates of a Horizontal Cylindrical Air-Tight Stove; and I do hereby declare that the said new design is fully described and represented in the following specification and accompanying drawings, to which reference is hereinafter made.

In the drawings, Figure 1 is an elevation of the front plate. Fig. 2 is an elevation of the back plate; and Figs. 3 and 4 are sectional views of the said front plate, taken in the planes of the lines A B and C D, respectively.

My new design consists in ornamenting the two plates above referred to (and which are shaped in outline as shown in Figs. 1 and 2, and have around their margins the plain ogee molding indicated at a a a and b b b, respectively, in the several figures) with scallop-shells and razor-shells, cast in alto-rilievo on the faces of said plates, as follows: On the door c c c of the front plate is the large central shell d, and above the same the two smaller ones e e, and below the same the two pointed ones f f. On each side of the upper part of the door is a razor-shell s s. On each

side of the draft-flue g is a scallop-shell h h, arranged in a diagonal position, and below said flue the razor-shell j, and at the central and upper salient points of the plate are the scallop-shells i i and k k. The rear or back plate has scallop-shells l l and m m at its central and upper salient points of the outline of the molding, and at the top, between those at m m, are the shells o o. The feet of both plates on which the stove is supported have along their bases the inclined rectangular raised ribs p p p, &c., and over these on each side are the razor-shells q q q q, cast in alto-rilievo, like the scallop-shells above referred to.

Having thus described my new design, what I claim as my production, and desire to have secured to me by Letters Patent, is—

The ornamental design hereinabove described for the front and back plates of a horizontal cylindrical air-tight stove and the door of the former, consisting of scallop-shells and razor-shells cast in alto-rilievo in the several positions on said plates hereinabove specified and represented in the drawings.

CALVIN DOANE.
